US0D1069855S

(12) **United States Design Patent** (10) **Patent No.:** **US D1,069,855 S**
(45) **Date of Patent:** **** Apr. 8, 2025**

(54) **EMBROIDERY MACHINE**

(71) Applicant: **BROTHER INDUSTRIES, LTD.**,
Nagoya (JP)

(72) Inventor: **Nozomi Tanaka**, Nagoya (JP)

(73) Assignee: **BROTHER INDUSTRIES, LTD.**,
Nagoya (JP)

(**) Term: **15 Years**

(21) Appl. No.: **29/841,993**

(22) Filed: **Jun. 9, 2022**

(30) **Foreign Application Priority Data**

Mar. 25, 2022 (JP) ..... 2022-006204 D
(51) LOC (15) Cl. **15-06**
(52) U.S. Cl. **D15/66**

(57) **CLAIM**

The ornamental design for an embroidery machine as shown and described.

DESCRIPTION

FIG. 1 is a front, top, right perspective view of the embroidery machine;

FIG. 2 is a front elevational view thereof;

FIG. 3 is a rear elevational view thereof;

FIG. 4 is a left-side elevational view thereof;

FIG. 5 is a right-side elevational view thereof;

FIG. 6 is a top plan view thereof;

FIG. 7 is a bottom plan view thereof;

FIG. 8 is a front, bottom, right perspective view thereof; and, FIG. 9 is a rear, bottom, left perspective view thereof.

The evenly spaced broken lines depict parts of the embroidery machine that form no part of the claimed design. The dot-dash chain lines depict a boundary of the claimed subject matter and form no part of the claimed design.

1 Claim, 7 Drawing Sheets
